UNITED STATES PATENT OFFICE.

MARCO CORTOPASS, OF PITTSBURGH, PENNSYLVANIA.

SAND TOY.

1,304,456.

Specification of Letters Patent.

Patented May 20, 1919.

Application filed May 3, 1918. Serial No. 232,224.

To all whom it may concern:

Be it known that I, MARCO CORTOPASS, a citizen of the United States, residing at Pittsburgh, in the county of Allegheny and State of Pennsylvania, have invented certain new and useful Improvements in Sand Toys, of which the following is a specification.

This invention relates to sand toys and has for its object to provide a toy of such class and with means, in a manner as herein-after set forth, including a miniature figure, actuated by sand impacted against a revolving element, to set up the appearance of a juggler juggling a spherical element.

Further objects of the invention are to provide a sand toy, which is simple in its construction and arrangement, amusing to children when operated, strong, durable, conveniently operated and inexpensive to manufacture.

With the foregoing and other objects in view this invention consists of the novel construction, combination and arrangement of parts as hereinafter more specifically described and illustrated in the accompanying drawing wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a front elevation of a sand toy in accordance with this invention.

Fig. 2 is a section on line II—II, Fig. 1.

Fig. 3 is a section on line III—III, Fig. 2.

Fig. 4 is a section on line IV—IV, Fig. 2.

Referring to the drawings in detail 1 denotes an oval shaped casing, open at its bottom, and partly closed at its top by a plate as at 2. As the length of the plate 2, is such, as not to completely close the top of the casing 1, an inlet 3, is provided.

The open bottom or lower end of the casing 1, has inwardly extending deflectors 4, which depend below the bottom of said casing 1, and act as means to deflect the sand 5, into a cup or receptacle 6, which is positioned below the casing 1, the latter being suspended above said receptacle 6, by legs

or standards 7, which are attached as at 8, to the lower portions of the side walls of the casing 1.

The front wall of the casing 1, near its lower end has projecting forwardly therefrom a platform 9, which supports a miniature figure 10, representing a juggler or clown. The arms of said figure 10, are indicated at 16, and the hands at 13. The arms are formed of fabric. Arranged against the rear of each of the arms 16, is a curved spring, which are indicated at 11, 12. The outer ends of the springs 11, 12, are connected to the hands 13, and their inner ends attached to an oscillatory lever arm 14, arranged at the rear of and supported from the figure 10, as at 15. The arms 11, 12, conceal the springs 11, 12.

Journalized in the casing 1, and extending transversely therefrom is a revolving shaft 16, carrying a rotor in the form of a wheel 17, provided with radial buckets 18. The shaft 16, is extended from the front of the casing 1, and cranked as at 19. Loosely connected to the cranked end 19, of the shaft 16, is an elongated link 20, which is pivotally connected as at 21, to the oscillatory lever 14.

Pivotally secured to the rear of the figure 10, below the pivot 15, as at 21, is a bar 22, which may be formed of resilient material and which carries on its outer end a spherical member 23. The lower end of the bar 22, is offset and bears against a bow shaped spring 24.

Suspended above the casing 1, by the inclined supports 25, is an inverted conical receptacle 26, having an outlet 27, at its lower end, and which is arranged over the inlet 3. The receptacle 26, is adapted to contain a charge of sand 5, and when the sand is discharged from the receptacle 26, passes down the inlet 3, and into the casing 1, which impacts against the buckets 18, revolving the wheel 17, which in turn revolves the shaft 16, the latter shifting the link 20, thereby oscillating the lever 14. During the oscillation of the lever 14, the arms 11, 12, will be carried therewith and the hands 13, alternately engaging the member 23, will shift the same from hand to hand, giving the appearance of juggling a ball or other object.

The discharge of sand from the receptacle

26, is controlled by gate 28, which is pivoted on a post 29, supported from the receptacle 26. The gate 28, has a handle 30.

What I claim is:

- 5 1. A sand toy comprising means to provide the representation of a human figure including a pair of arms, an oscillatory lever pivotally supported by said means and having said arms connected therewith, said arms 10 having means to provide the representation of hands, a rod pivotally supported from the figure and carrying a spherical member at its outer end adapted to be alternately engaged by the representation of the hands to shift said member in opposite directions, a rotor operated by a charge of sand and including a shaft, and an operative connection between said lever and said shaft for oscillating the lever.
- 15 2. A sand toy comprising a rotor operated by the impact of sand and including a shaft, an oscillatory lever, a support therefor, an operative connection between the lever and shaft and for oscillating the lever when the

rotor is operated, an element pivoted to said support and carrying a spherical object, and a pair of elements connected to said lever and alternately striking said spherical object for shifting it in opposite directions.

3. A sand toy comprising a rotor including radially disposed buckets successively receiving a charge of sand for revolving the rotor, said rotor further including a revolving shaft, an oscillatory lever, a support therefor, an operative connection between 35 said lever and said shaft for oscillating the lever when the rotor is operated, a spherical element, a carrier therefor, and means connected with said lever and alternately striking said spherical element during the oscillation of the lever for shifting the said spherical element alternately in opposite directions.

In testimony whereof I affix my signature.
MARCO CORTOPASS.
